UNITED STATES PATENT OFFICE.

TAUBE DAVIS, OF NEW YORK, N. Y., ASSIGNOR TO FRANKLIN SIMON & CO. INC., OF NEW YORK, N. Y., A CORPORATION OF NEW YORK.

DESIGN FOR A DRESS.

Application filed August 12, 1926. Serial No. 18,704. Term of patent 3½ years.

To all whom it may concern:

Be it known that I, TAUBE DAVIS, a citizen of the United States, and a resident of the city of New York, borough of Manhattan, in the county and State of New York, have invented a new, original, and ornamental Design for Dress, of which the following is a specification, reference being had to the accompanying drawing, forming part thereof, wherein the dress is distinguished by a jumper or tunic having a group of spaced tucks extending from the shoulder downwardly a short distance on each side of the neck opening, an ornamental tapering neck

ornament merging into a tongue and a looped portion overlapping the same. The dress is also distinguished by the lower edge of the tunic being provided with an ornamental band having a central section presenting ornamental blocks with ornamental buttons on diametrically opposite sides.

The figure is a front elevation of a dress, showing my new design.

I claim:

The ornamental design for a dress, substantially as shown and described.

TAUBE DAVIS.
